UNITED STATES PATENT OFFICE.

JOHN C. BARCLAY, OF NEW YORK, N. Y.

PRINTING-TELEGRAPH.

No. 877,822.

Specification of Letters Patent.

Patented Jan. 28, 1908.

Application filed January 11, 1907. Serial No. 351,863.

To all whom it may concern:

Be it known that I, JOHN C. BARCLAY, a citizen of the United States, residing at New York, in the county of New York and State of New York, have invented certain new and useful Improvements in Printing-Telegraphs; and I do hereby declare the following to be a full, clear, and exact description of the same, such as will enable others skilled in the art to which it appertains to make and use the same.

My invention relates to improvements in printing telegraphs, and comprises a system of the synchronous class, wherein finger keys of a transmitting instrument control, through synchronously-operated commutators or "sunflowers" at both the transmitting and receiving station, the several magnets of a receiving printer. This printer is preferably of the page-printing type, comprising a plurality of character magnets corresponding respectively to different characters to be printed, each such magnet in a separate circuit connected to a particular contact point or segment of the corresponding sunflower. Printers of such type adapted for connection to and control by sunflowers in the manner described, are shown in my Patents No. 787,608, dated Apr. 18, 1905, and No. 811,995, dated February 6, 1906. The system herein described is particularly adapted for relatively short lines, or lines in which the capacity and resistance are relatively small and for that reason sharply-defined current pulses succeeding each other with extreme rapidity are obtainable, and over which direct transmission between operators is desired, as distinguished from systems in which messages are impressed upon or perforated in tapes for operating automatic transmitters. Instances where this direct service is particularly desirable are; circuits connecting different telegraph offices in the same city; circuits connecting a central office or distributing point with various cities or towns in the surrounding territory; and railway telegraph or block-signal service. The simplicity of the apparatus required, the ease with which it may be operated by any person familiar with a typewriter keyboard, and the relatively high speed of transmission obtainable as compared with ordinary hand or "Morse" transmission, also the legibility of the message as written out by the receiving instrument, render such a system particularly suitable for the kinds of service speci-

fied, as well as for many other kinds of service which it is hardly necessary to enumerate.

The object of my invention is to permit direct transmission over a single circuit from a keyboard transmitter to a receiving printer, in either direction at will, and by simple mechanism capable of relatively rapid operation.

I will now proceed to describe my invention with reference to the accompanying drawings, illustrating the system diagrammatically and also certain apparatus convenient to use therein, and will then point out the novel features in claims.

In said drawings—Figure 1 is a diagram showing the circuits of the system. Fig. 2 is a top view of the sunflower mechanism and associated parts. Fig. 3 is a detail side view of the sunflower. Fig. 4 is a detail side view of the stop mechanism. Fig. 5 is a detail side view of the escapement mechanism. Fig. 6 is a detail elevation of the synchronizing mechanism. Fig. 7 is a detail view of a mechanical pole changer which may be used in lieu of the commutator shown for that purpose in Figs. 1 and 2.

Referring first to Fig. 1, I have shown a system comprising two stations, 1 and 2, connected by a single line wire 3; each station having a full equipment of transmitting and receiving apparatus. The apparatus at both stations being the same, it is necessary to describe that at one station only.

4 designates the transmitting keyboard diagrammatically. It comprises a plurality of finger keys corresponding to the several characters, symbols etc. to be transmitted, each key operating an individual contact device. Keyboards of this type are well known, and it is not necessary to illustrate the detail construction of the device. Each finger key contact is connected by a conductor 5 to a corresponding segment of the transmitting sunflower 6 at its home station, and also to a corresponding control or character magnet 7 of the home receiving printer. I have employed these character magnets 7 as a diagrammatic designation of the receiving printers, in Fig. 1; it being understood, of course, that the mechanism of the printer may be anything suitable to be controlled by a series of magnets, such as shown.

Referring now both to Fig. 1 and to the remaining figures, and particularly to Fig. 2, sunflower 6 is operated by a driving shaft 8, driven by a suitable motor 9 through an or-

dinary slip-permitting friction drive 10, the detail construction of which it is not deemed necessary to show, as such devices are well known. On said shaft 8 is a contact brush 11 adapted to sweep over the segments 12 of the sunflower successively as the shaft revolves. On said shaft 8 there is also a ratchet wheel 13, arranged to be engaged by the stop-armature 14 of a stop-magnet 15, and thereby to arrest the rotation of shaft 8 whenever the circuit of said magnet 15 is completed. As will be seen by reference to Fig. 1, magnet 15 is interposed in the circuit 16 of the sunflower brush 11, between said brush and return (ground, in the instance shown), and so is energized whenever brush 11 reaches a sunflower segment the keyboard contact of which is closed. The slip-drive 10 permits the motor 9 to continue to rotate its driving shaft while shaft 8 is held stationary, and permits shaft 8 to pick up and begin to rotate promptly upon the release of ratchet wheel 13 by armature 14 following deenergization of magnet 15, which occurs whenever the finger-key contact connected to that sunflower contact upon which the brush 11 stops is broken.

Shaft 8, when rotating, drives a pole-changing device 16 connected to the line circuit and therethrough to the operating magnet 17 of an escapement mechanism of the apparatus at the receiving end of the line. The form of pole changing device which I have illustrated diagrammatically in Figs. 1 and 2 comprises the familiar commutator having brushes 18 connected to sources of current of different polarity, respectively, and riding upon contact hubs 19 connected to alternate peripheral sections of the commutator disk, 20, with which sections a brush 21 makes contact as the commutator disk 20 revolves.

In Fig. 1 I have illustrated, as sources of current of opposite polarity, opposed batteries 22; but I do not limit myself to any particular source of current. Brush 21 is connected to line 3 through a switch 23, and when said switch is in the position shown at station 1, Fig. 1, and when the corresponding switch at the other station is in the opposite position, will obviously send an alternating current through the line, while shaft 8 revolves; and since the contact segments of sunflower 6 and commutator 20 correspond, there will obviously be a change of line polarity for each passage of brush 11 over a sunflower segment.

Since the maintenance of synchronism between the transmitting and receiving instruments depends upon the faithful operation of the escapement mechanism of the receiving instrument, it is preferable, instead of following the obvious course of placing the escapement magnets 17 in the line circuit 3 itself, to control said escapement magnets

by local circuits operated by sensitive relays placed in the line circuit. Thereby the sharp response of the escapement mechanism to rapidly-recurring alternations in the line circuit is facilitated, and likewise the line circuit is freed of unnecessary resistance and retardation, for the relays used may have much less resistance and retardation than the escapement magnets. Numerals 24, in Fig. 1, designate the said relays, in the line circuit as shown, and controlling escapement magnets 17 through local circuits 25 and arranged to reverse polarity therein as polarity in the line circuit changes.

In this system, as in ordinary ticker systems, distinction is made between those line current pulses which are merely to operate the escapement mechanism of the receiving printer and so advance the sunflower brush 11 of the receiving printer, and those line current pulses which are to cause the printing of a character, by prolonging the printing pulses; which is done by arresting momentarily the brush of the transmitting sunflower while it is in contact with the sunflower segment corresponding to the finger key depressed. In ticker systems, printing is effected by means of these prolonged pulses, by means of a press arm operated by a magnet in the line circuit which is too sluggish to respond to ordinary current pulses, and responds only to the prolonged pulses intended to effect the operation of said press arm and the printing of characters. Such a press arm and sluggish press magnet are too slow in operation, require too much current, and place too much resistance and retardation in the line, for use in my system. Instead I use a delicate relay, termed a "separator" relay, at each station. Numerals 26 designate the said separator relays. Like the escapement magnets 17, they are in the local circuits controlled by line relays 24. Without limiting myself to any particular construction of separator relay, I have illustrated diagrammatically a relay having an arrangement of contact points convenient for the purpose. The same comprises a T-headed armature 27 carrying contact springs 28 and 29 adapted to make contact respectively with stop screws 30 and 31. Contact is complete from screw 30 to screw 31 only during the instant when, as the armature 27 moves across, both springs are in contact with their respective screws; and the adjustment of the relay is such that this can occur only when a prolonged pulse has operated relay 24 and caused the latter to prolong the pulse in local circuit 25.

The adjustment of a separator relay such as that shown, so that it will not respond to short pulses, but only to long pulses, is quite easy; and such a relay will distinguish between pulses the difference in duration of which is relatively small.

The separator relays I commonly place in the common return circuit 32 of the several character magnets 7 of the printers, arranging said relays to complete said printer return circuit only when a long pulse is transmitted. 33, in the same return circuit, may be understood to be a magnet, of the printer, which must be energized, as well as one of the character magnets 7, in order that a character may be printed. In the particular printing telegraph shown in my said Patent No. 787,608, this magnet 33 may be understood to be the clutch or spacing magnet of the machine, without the energization of which no character will be printed. In this same return circuit 32 I commonly place a switch 34, by means of which the return circuit may be broken. By opening or closing this switch, the transmitting operator may cause the printer at his station to operate in unison with the printer at the receiving station, and so to print the message transmitted, or not, as he desires. In synchronous systems such as this, it is usually necessary to provide some means for synchronizing the apparatus at the two ends of the line, at intervals. It may happen for example, that owing to a "swing" of the line wire or other disturbance, one or more of the pulses produced by the transmitting apparatus will be lost so far as the receiving apparatus is concerned. To this end I provide the apparatus at both ends of the line with synchronizing means which in principle is the same as that commonly used on tickers, comprising a worm 35 on the shaft 8, an arm 36 having a projection adapted to engage said worm, said arm pivoted so that when said projection engages the worm and the worm revolves the arm will be moved to the left of Fig. 6, and a magnet 37, the armature 38 of which, when attracted by said magnet, moves arm 36 away from said worm 35, causing it to be pulled back to the right by its spring 39. To bring the apparatus at the two ends of the line into synchronism the operator whose apparatus is behind that of the other operator, sets his switches 23 and 34 for transmission, and causes his transmitting apparatus to transmit through the line a long series of short alternations which he may do by allowing the shaft 8 to rotate without depressing any finger keys. Thereby the worms 35 of both transmitting apparatus are caused to revolve and move their respective arms 36 to the left until said arms encounter the projections 40 and so stop the rotation of their shafts 8. The shaft of the instrument at the distant end of the line will obviously be arrested first, and then, as soon as the shaft of the apparatus which is then transmitting is also arrested, the pulse then being transmitted through the line is prolonged owing to the stopping of shaft 8, and this operates magnet 37 of both instruments causing said

magnets to withdraw their arms 36 and so to permit the shafts 8 to revolve again. Projections 40 of shafts 8 being in corresponding positions, and the shafts having therefore been arrested in corresponding positions 70 and being released simultaneously, synchronism is restored upon the release of the shaft just specified.

The operation of the system is as follows: The operator at one station, for example 75 station 1, desiring to transmit to the operator at the other station, will signal the latter by his hand key to start his motor 9. The operator desiring to transmit will likewise start his motor; and after a sufficient interval 80 to allow the two apparatus to be brought into synchronism in the manner above described, the transmitting operator depresses the finger keys of his key-board in the proper order to print the desired message. Each finger key when depressed closes a circuit from battery 41 (Fig. 1) to the corresponding segment of its sunflower 6; and as soon as the brush 11 of that sunflower reaches such segment the circuit will be completed through 90 the brush and stop magnet 15, thus causing the armature 14 of that magnet to engage ratchet wheel 13 and stop shaft 8. During the rotation of the shaft 8 of the transmitting instrument, the alternations sent through the line by the pole changer 16 of that transmitter have caused the operation of the escapement magnet 17 of the instrument in the other end of the line, permitting the shaft 8 of that instrument to advance, the sunflower brush 11 maintaining synchronism 95 with the corresponding brush of the transmitting instrument. As soon as the shaft 8 of the transmitting instrument comes to rest, as described, the alternations in the line 100 cease and thereby shaft 8 of the receiving instrument also comes to rest, whereupon a circuit is completed from the battery 41 of the receiving instrument through the sunflower brush 11 of that instrument, the sunflower segment with which that brush is in contact at the moment and the magnet 7 thus selected to the common return conductor 110 32, the magnet 33 and the contacts of the separator relay 26. While the shaft of the receiving instrument has been rotating circuits completed through magnets 7 have been completed for too brief a time for the return circuit to be closed through the contacts of separator relay 26, but the line pulse 115 being now prolonged owing to the momentary stoppage of transmitting shaft 8, the contact mechanism of separator relay 26 completes the return circuit through magnets 7 and 33 causing the printer to operate 120 and print a character.

As soon as the finger key which was depressed has been released, the circuit of stop magnet 15 will be broken and both shafts 8 will begin to rotate again in unison. 130

It will be obvious that if the switch 34 of the transmitting instrument be closed, both printers will be operated in the manner described, both printing the message transmitted.

- 5 In the above description, and in the following claims, I have used the terms "sunflower" and "sunflower distributor", as terms generic to any type of distributing 10 commutator comprising a rotating member adapted to complete a plurality of contacts successively; and I have used the term "character magnets" as denoting magnets corresponding to particular characters and 15 adapted when energized to cause the printing of such characters (for example, the magnets 24 of my Patent No. 787,608) instead of magnets which, by coöperation with other similar magnets, operate selecting mechanism to bring one or another of the characters 20 to be printed into printing position.

In lieu of the commutator pole changer shown in Figs. 1 and 2, I may use the alternative construction shown in Fig. 7 comprising an electro-magnetic pole changer 41 (that shown being what is known as a walking beam pole changer) in a circuit controlled by contact points 42 and 43, arranged to be separated and contacted alternately by a 30 cam 44 on the main shaft 8 of the transmitter.

What I claim is:

1. A printing telegraph comprising in combination transmitting means including 35 pulsatory-current producing means arranged to produce periodic current pulses in a line and means for prolonging at will any one of such pulses; a line circuit; and receiving means including a plurality of character- 40 magnets corresponding each to a different character, and corresponding in number to the characters to be printed, one or another of said magnets adapted singly to cause the printing of any one of such characters, a 45 sunflower selector comprising contacts for the different character magnets, and a separator relay controlled by the line circuit and controlling the circuits through said sunflower to the several character magnets and arranged when operated by a prolonged 50 pulse to cause the character magnet in circuit at that instant through the sunflower to operate.

2. A printing telegraph comprising in combination transmitting means including 55 pulsatory-current producing means arranged to produce periodic current pulses in a line, and a key board and means operated thereby for prolonging at will any one of said pulses; 60 a line circuit; and receiving means including a plurality of character magnets corresponding each to a different character, and corresponding in number to the characters to be printed, one or another of said magnets 65 adapted singly to cause the printing of any

one of such characters, a sunflower selector comprising contacts for the different character magnets, and a separator relay controlled by the line circuit and controlling the circuits through said sunflower to the several 70 character magnets and arranged when operated by a prolonged pulse to cause the character magnet in circuit at that instant through the sunflower to operate.

3. A printing telegraph comprising in combination transmitting means comprising a pole changer and controlling means arranged at will to arrest said pole changer; a line circuit to which said pole changer is connected; and receiving means including a 80 plurality of character magnets corresponding each to a different character, and corresponding in number to the characters to be printed, one or another of said magnets adapted singly to cause the printing of any 85 one of such characters, a sunflower selector comprising contacts for the different character magnets, and a separator relay controlled by the line circuit controlling the circuits through said sunflower to the several 90 character magnets and arranged when operated by a prolonged pulse to cause the character magnet in circuit at that instant through the sunflower to operate.

4. A printing telegraph comprising in 95 combination transmitting means including a pole changer, a key board and means operated thereby for arresting said pole changer at will, and prolonging the current pulse produced thereby at the instant of 100 such arrest; a line circuit; and receiving means including a plurality of character magnets corresponding each to a different character, and corresponding in number to the characters to be printed, one or another 105 of said magnets adapted singly to cause the printing of any one of such characters, a sunflower selector comprising contacts for the different character magnets, and a separator relay controlled by the line circuit and controlling the circuits through said sunflower to the several character magnets and arranged when operated by a prolonged pulse 110 to cause the character magnet in circuit at that instant through the sunflower to operate.

5. A printing telegraph comprising in combination transmitting means including a sunflower and controlling devices corresponding to different characters to be printed and connected to different contacts 120 of said sunflower, means operated in synchronism with the operation of said sunflower arranged to produce periodic current pulses in a line circuit, and means causing the operation of any one of said controlling 125 devices to effect prolongation of the corresponding current pulse; a line circuit; and receiving means including character-magnets corresponding each to a different character and corresponding in number to the char- 13

acters to be printed, a sunflower selector operated in synchronism with said transmitter sunflower and comprising contacts for the different character magnets, and a separator relay controlled by the line circuit and controlling the circuits through said receiving sunflower and character magnets and arranged when operated by a prolonged pulse to cause the character magnet selected at that instant by said receiving sunflower to operate.

6. A printing telegraph comprising in combination transmitting means including a sunflower, a key board having character contacts connected to different contacts of said sunflower, and arresting means arranged to arrest said sunflower and controlled by said sunflower contacts and character contacts, whereby when a character contact and the corresponding sunflower contact are closed said sunflower is arrested, and means operated in synchronism with the operation of said sunflower arranged to produce periodic pulses in a line circuit; a line circuit; and receiving means including character-magnets corresponding each to a different character and corresponding in number to the characters to be printed, a sunflower selector operated in synchronism with said transmitter sunflower and comprising contacts for the different character magnets, and a separator relay controlled by the line circuit and controlling the circuits through said receiving sunflower and character magnets and arranged when operated by a prolonged pulse to cause the character magnet selected at that instant by said receiving sunflower to operate.

7. A printing telegraph comprising in combination transmitting means including a sunflower and controlling devices corresponding to different characters to be printed and connected to different contacts of said sunflower, means operated in synchronism with the operation of said sunflower arranged to produce periodic current pulses in a line circuit, and means causing the operation of any one of said controlling devices to effect prolongation of the corresponding current pulses; a line circuit; and receiving means including character-magnets corresponding each to a different character and corresponding in number to the characters to be printed, a sunflower selector operated in synchronism with said transmitter sunflower and comprising contacts for the different character magnets, and a separator relay controlled by the line circuit and controlling the circuits through said receiving sunflower and character magnets and arranged when operated by a prolonged pulse to cause the character magnet selected at that instant by said receiving sunflower to operate; said receiving means further comprising electro-magnetic synchronizing

means operated by current pulses in said line circuit for maintaining synchronism of the receiving sunflower with the transmitting sunflower.

8. A printing telegraph comprising in combination transmitting means including a sunflower and controlling devices corresponding to different characters to be printed and connected to different contacts of said sunflower, and a pole changer operated in synchronism with the operation of said sunflower arranged to produce periodic current pulses in a line circuit, and means causing the operation of any one of said controlling devices to effect prolongation of the corresponding current pulse; a line circuit; and receiving means including character-magnets corresponding each to a different character and corresponding in number to the characters to be printed, a sunflower selector operated in synchronism with said transmitter sunflower and comprising contacts for the different character magnets, and a separator relay controlled by the line circuit and controlling the circuits through said receiving sunflower and character-magnets and arranged when operated by a prolonged pulse to cause the character magnet selected at that instant by said receiving sunflower to operate.

9. A printing telegraph comprising in combination transmitting means including a sunflower, a key board having character contacts connected to different contacts of said sunflower, arresting means arranged to arrest said sunflower and controlled by said sunflower contacts and character contacts, whereby when character contacts and corresponding sunflower contacts are closed, said sunflower is arrested, and a pole changer operated in synchronism with the operation of said sunflower arranged to produce periodic current pulses in line circuit, and means causing the operation of any one of said controlling devices to effect prolongation of the corresponding current pulse; a line circuit; and receiving means including character-magnets corresponding each to a different character and corresponding in number to the characters to be printed, a sunflower selector operated in synchronism with said transmitting sunflower and comprising contacts for the different character magnets, and a separator relay controlled by the line circuit and controlling the circuits through said receiving sunflower and character magnets and arranged when operated by a prolonged pulse to cause the character magnet selected at that instant by said receiving sunflower to operate.

10. A printing telegraph comprising in combination a line circuit and combined transmitting and receiving means at each end thereof and each comprising printing means including character magnets corresponding

- each to a different character and corresponding in number to the characters to be printed, a key board having character contacts, a sunflower having character contacts each corresponding to and connected to one of said character magnets and one of said key board character-contacts, pulsatory-current producing means operated synchronously with the sunflower, pulse-prolonging means controlled by the several character-contacts, and a separator relay controlled by the line circuit and controlling the circuits through said receiving sunflower and character magnets.

11. A printing telegraph comprising in combination a line circuit and combined transmitting and receiving means at each end thereof and each comprising printing means including character magnets corresponding each to a different character and corresponding in number to the characters to be printed, a key board having character contacts, a sunflower having character contacts each corresponding to and connected to one of said character magnets and one of said key board character-contacts, pulsatory-current producing means operated synchronously with the sunflower, pulse-prolonging means controlled by the several character-contacts, and a separator relay controlled by the line circuit and comprising an armature and contacts closed only during the movement thereof, controlling the circuit through said sunflower and character magnets.

12. A printing telegraph comprising in combination a line circuit and combined transmitting and receiving means at each end thereof and each comprising printing means including character magnets corresponding each to a different character and corresponding in number to the characters to be printed, a key board having character contacts, a sunflower having character contacts each corresponding to and connected to one of said character magnets and one of said key board character-contacts, pulsatory-current producing means operated synchronously with the sunflower, pulse-prolonging means controlled by the several character contacts, and a separator relay controlling the circuits through said receiving sunflower and character magnets, and means for synchronizing the sunflowers.

13. A printing telegraph comprising in combination a line circuit and combined transmitting and receiving means at each end thereof and each comprising printing means including character magnets corresponding to a different character and corresponding in number to the characters to be printed, a key board having character contacts, a sunflower having character contacts each corresponding to and connected to one of said character magnets and one of said key board character-contacts, pulsatory-current producing means operated synchronously with the sunflower, pulse-prolonging means controlled by the several character-contacts, and a separator relay controlled by the line circuit and comprising printing means including character magnets corresponding each to a different character and corresponding in number to the characters to be printed, a key board having character contacts, a sunflower having character contacts each corresponding to and connected to one of said character magnets and one of said key board character-contacts, pulsatory-current producing means operated synchronously with the sunflower, pulse-prolonging means controlled by the several character-contacts, and a separator relay controlled by the line circuit and comprising an armature and contacts closed only during the movement thereof, controlling the circuit through said sunflower and character magnets.

14. A printing telegraph comprising in combination a line circuit and combined transmitting and receiving means at each end thereof and each comprising printing means including character magnets corresponding each to a different character and corresponding in number to the characters to be printed, a key board having character contacts, a sunflower having character contacts each corresponding to and connected to one of said key board character-contacts, pulsatory-current producing means operated synchronously with the sunflower, pulse-prolonging means controlled by the several character contacts, a separator relay controlling the circuits through said receiving sunflower and character magnets, an electro-magnetic escapement for each sunflower and a receiving relay in the line circuit and a local circuit controlled thereby and controlling said escapement and said separator relay.

In testimony whereof I affix my signature, in the presence of two witnesses.

JOHN C. BARCLAY.
